UNITED STATES PATENT OFFICE.

HERMAN FRASCH, OF CLEVELAND, OHIO, ASSIGNOR TO THE SOLAR REFINING COMPANY, OF OHIO.

PROCESS OF REFINING LIMA OR SIMILAR PETROLEUM.

SPECIFICATION forming part of Letters Patent No. 564,923, dated July 28, 1896.

Application filed December 17, 1894. Serial No. 532,077. (No specimens.)

To all whom it may concern:

Be it known that I, HERMAN FRASCH, a citizen of the United States, residing at Cleveland, in the county of Cuyahoga and State of Ohio, have invented certain new and useful Improvements in Processes of Refining Lima or Similar Petroleum; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to the removal from Lima or similar petroleum of what is known as "skunk" among workers in that class of oil, the said skunk resisting removal (as is well known) by the ordinary sulfuric-acid and alkali treatment, by which oils of the Pennsylvania class have long been satisfactorily refined; but each part of the invention is, of course, intended to be secured for all the uses to which it may be applicable.

Skunk-bearing oils are found not only about Lima, Ohio, (whence the name,) but also in other parts of Ohio, in Canada, and to a less extent in States of the Union other than Ohio. As they come from the well they contain a very considerable percentage of sulfur, (usually upward of one-half of one per cent.,) have a penetrating disagreeable odor, and dissolve litharge (lead oxid) in considerable proportions, the peculiar odor and the property of dissolving litharge without the aid of oleic acid, rosin, or other added agent being believed to be characteristic of them and proving the presence of skunk in the oil. The burning oil distillates from ordinary distillation of skunk-bearing petroleum, (whether given the ordinary sulfuric-acid and alkali treatment or not,) have the skunk odor, and dissolve litharge. When tested by the addition of a small quantity of an aqueous solution of plumbate of soda, they turn yellow, provided they have previously been freed from sulfureted hydrogen. Otherwise this latter substance causes a dark or black discoloration. On burning in lamps they give a bad odor and cause a cloud on the chimney and a crust on the wick. There has, how-

ever, been long known a process (commonly called the "Canadian" treatment) by which the burning oil from Lima petroleum can be deprived of its odor and of the property of dissolving litharge without, however, removing the skunk, for on redistillation of Canadian-treated oil the skunk odor reappears and the distillate from such redistillation dissolves litharge and (if free from sulfureted hydrogen) turns yellow with plumbate of soda solution. On burning in lamps the Canadian-treated oils give a bad odor, cloud the chimney, and crust the wick. By the Canadian treatment, therefore, the skunk is concealed, but not removed.

For the purpose of removing the skunk from this class of oils I have heretofore devised a number of processes and apparatus. I discovered, among other things, that the skunk could be made to react with suitable substances having a basis of metal, and could thus be decomposed, with the formation of a metallic sulfur compound, easily separable from the hydrocarbons; and I further discovered various modes whereby such reaction could be brought about industrially.

I obtained very successful results by distilling the skunk-bearing oil with the decomposing substance dissolved therein, and also by vaporizing the oil and passing the skunk-bearing vapors through or over an oily or resinous liquid holding the substance in solution or solution and suspension therein. Further, I obtained useful results in the decomposition of the skunk by the substance in a solid state instead of in solution in an oily or resinous liquid, the said substance being in the form of a more or less finely-ground powder or in larger pieces or lumps.

In accordance with the present invention skunk-bearing vapors are subjected to a purifier composed of a refractory fibrous material like woolly asbestos and a solid finely-divided skunk-decomposing substance adherent to the fibers of such material. It is an advantage and a special improvement to use a skunk-decomposing substance having a basis of copper or like metal, (by which here and elsewhere in this specification is meant a metal whose oxid is soluble in skunk-bearing oil,) because such substance effects a decom-

position of the skunk at temperatures below those which cause a substantial decomposition of the hydrocarbons and formation of permanent gases, and which are apt to give a scorched appearance and odor to the distillate.

The best mode of charging the asbestos with the skunk-decomposing substance is to stir the latter as a fine powder into a thin pulp of asbestos, which is then dried. The asbestos takes up the powder which adheres thereto. The powdered substance may be such as at once to act as a skunk-decomposer, (say, for example, black oxid of copper,) or it may 15 when mixed with the pulp be in an inactive condition and require a treatment before it will decompose skunk. Thus copper sulfid does not decompose skunk, but by oxidation it becomes converted into the sulfate (provided sulfur dioxid is not eliminated) or into the oxid, (if sulfur dioxid be given off,) either of which is an active decomposer of skunk in oil-vapors. Such oxidation can be performed 20 after the copper sulfid has been stirred into the asbestos pulp and the latter dried. Further, I have discovered that the skunk-decomposing substance can be made to assume a peculiar state in which it is materially expanded or swelled beyond the ordinary ground 25 form of such substance or even that of an ordinary precipitate, and in such state can be used while adherent to asbestos or asbestos-like material.

In charging the asbestos with the skunk-decomposing substance it suffices to apply the latter in the ordinary ground condition or in the precipitated form, whether the application be by stirring the dense substance into asbestos pulp or otherwise. The swelled or expanded state can then be given to the adherent substance by suitable change of chemical composition under conditions of pressure and temperature adapted to the retention of such state, all as hereinafter more fully set forth.

To support the purifier (consisting of the skunk-decomposing substance and the asbestos or refractory fibrous material, to which it is adherent) in such a manner that the oil-vapors to be purified can have full access to such substance, and that they do not pass by short cuts over certain portions only of the purifier, the said purifier is placed in layers on horizontal or inclined plates or trays in a zigzag vapor-duct. The oil-vapors being thus compelled to take a roundabout course and to pass over an extended body of the purifier are the more apt to act upon every particle of the skunk-decomposing substance 50 and to have every particle of the skunk acted upon and decomposed by such substance. The best arrangement is to have at intervals in the duct a number of these plates and purifier-layers vertically superposed or made 55 into a pile with passages between each layer and the plate or tray above.

After the skunk-decomposing substance

has become inactive through the union of its metal with sulfur from the oil-vapors its activity is restored by burning, or, in other words, oxidation, and this burning is best effected below such a temperature as would suffice to cak the said substance, (when of a fusible nature, like copper compounds,) while yet sufficiently high to effect the revivification 70 in a reasonable time. To allow the burning to proceed with the greater rapidity without raising the temperature unduly, the heat is carried off by a cooling medium as said heat is generated.

In the accompanying drawings an apparatus is illustrated which is considered most suitable for carrying the invention into effect.

Figure 1 is a side view or elevation of such apparatus, partly in section, with a middle portion of the still taken out in order to get the figure on the sheet. Fig. 2 is a partial plan of the same, partly broken away to illustrate the construction in horizontal section. Fig. 3 is a vertical section on line *i i i* of Fig. 1, and Fig. 4 is a detail view.

The still A is shown as a cylinder-still of ordinary construction, except for the pipe connections with the chamber B, which forms the jacket of the purifier-boxes C C'. This chamber or jacket communicates at the bottom through the large pipe 2 with the liquid-space, and at the top through the pipe 3 with the vapor-space, of the still, so that during a run the oil stands at the same level in the 100 said chamber or jacket as in the still. The cover 4 closes the top of the chamber vapor-tight. The object of this arrangement is to maintain the temperature of the purifier through the medium of the oil in the still. 105 The purifier might be kept hot by any ordinary or suitable arrangement, such as a separate fire, or the fire-gases from under the still applied directly or through an ordinary sand or liquid bath.

In keeping up the temperature by the liquid oil such temperature would rise gradually as distillation proceeds. With other heating arrangements it might be raised gradually or it might be kept at a constant high temperature during a part and, if the range of gravities be not too great, during the whole of a run.

Underneath the chamber or jacket B are flues 5, (see Fig. 2,) conveying the products of 120 combustion from the space beneath the still to the chimney, whose position is shown at 6. They supply heat to keep up the temperature of the jacketing fluid. The maintenance of the purifier's temperature by the 125 liquid oil could be secured by having the purifier within the still instead of within a communicating chamber or jacket.

The purifier-boxes C C' rest on posts 7, which in turn rest on the bottom of the jacketing-chamber B. Two of these boxes are shown, but the number is not essential. Within each box are supports, to wit, cross-bars 8 and brackets 9, for supporting the floor-

plates 10, by which the box is divided into a vapor-duct *c c'*, respectively, rising in a zig-zag fashion from the bottom of the box. At each end of the box every alternate floor terminates at a distance from the end wall of the box, so as to make the duct run back and forth lengthwise of the box. On the several floors are piles of many trays D, each provided with a layer E of the purifier composed of the skunk-decomposing substance and the woolly asbestos, to the fibers of which such substance adheres.

Preferably a thin pulp of asbestos is made with water and the finely-divided substance (in an active or an inactive condition) stirred into it. The pulp is then dried. During the admixture the substance is kept suspended. It adheres to the asbestos fibers like a dye.

If a cupreous substance is used, as is preferred, black oxid of copper from any convenient source, ground, say fine enough to pass through a bolting-cloth having one hundred meshes to the inch, will answer, but it is better to use copper oxid procured from carefully roasting the residue resulting from using an oily solution of copper oxid in a skunk-removing operation. Finely-ground copper sulfid or sulfate can be used. Precipitated copper compounds, as sulfid or hydroxid, can be used. The mention of these is not, of course, intended to exclude the use of other forms. A layer E of the purifier, prepared as just described, is placed on each tray.

The trays are shown as held apart by separators in the form of sleeves 11, Fig. 4, above and below, so as to form passages over the purifier E. Bolts 12 pass through the trays D and sleeves 11 and clamp the charged trays of each pile together. The piles of trays are separated from one another and the two end walls of the boxes by spaces F, forming the chambers in the duct. The tops of the boxes C C' are removable, and the floor-plates and piles of trays are introduced through the top. First the bottom is supplied with piles of charged trays, (the same as indicated on the third floor above in Fig. 3 of the drawings,) then the floor-plates and piles of charged trays of the floor next above are introduced, and then those of higher and higher floors. Finally the top is put on. Other suitable constructions could be used. The trays might be inclined instead of horizontal, if preferred.

The purifier-boxes C C' are fastened to each other and to the walls of the chamber or jacket B by stays 13. The top of the vapor-duct in box C is connected with the bottom of the vapor-duct in box C' by means of the pipe 14. The pipe 16 leads from the vapor-space of the chamber B to the vapor-duct at the bottom of box C and the pipe 16 from the vapor-duct at top of box C' to the condenser. (Not shown.) The pipe 15 might of course lead from the vapor-space of the still A. In either case it

would receive the vapors from both the still A and chamber B.

The vapor-pipes 3 and 16, as shown, are severally provided with a removable section 7c 3' and 16', respectively, for breaking the still and condenser connections when desired. A plate (not shown) may be bolted to the flange 2', so as to close the inlet of pipe 2 whenever it is desired to cut the chamber B off from the still A. A similar plate may be bolted to the flange 15' when it is desired to close the pipe 15. The chamber B is further provided with manholes 17, with a water-supply pipe 18, and a draw-off 19.

The boxes C C' have air-inlet pipes 20 and 21, extending through the jacket B to the outside. There is one of these pipes for each floor. It can be closed with a removable plate or plug, and when open can, if necessary, have the inlet-openings adjusted by means of perforated plates, or reducers, or the like. The boxes also have each a draw-off 22 and 23, respectively, with a stop-cock therein, as shown for the box C in Fig. 3. In case oil should leak into the boxes, the draw-offs serve to remove it, but it is intended to have the boxes tight. The boxes C C', being charged with the purifier disposed in thin layers E on the trays D, are closed, and if the skunk-decomposing substance of such purifier is in an active condition (say copper oxid) the said boxes are put into communication with the still A by the pipes 3 and 15, and with the condenser (not shown) by the pipe 16. The jacketing-chamber B is also put in communication with the still through the pipes 2 and 3. The water-pipe 18, the draw-off 19, the air-inlet pipes 20 and 21, and the draw-offs 22 and 23 are all closed.

The still A is filled to the usual level with, say, crude Lima oil, either containing the naphtha, or from which the naphtha has been separated. It might be supplied with distillate, either burning oil or naphtha, or other distillate, but crude oil is preferable. The oil flows through the pipe 2 into the chamber B and stands therein at the same level as in the still. The fire is started under the still and the oil heated to the distilling temperature. The skunk-bearing vapors pass by the pipe 15 into the portion of the vapor-duct *c* at the bottom of box C. Here, and in the duct above each floor 10, the volume of vapors is divided into numerous small streams flowing in the same horizontal direction between adjacent trays D over the corresponding thin layers of asbestos and finely-divided skunk-decomposing substance, maintained by the oil at a temperature to prevent condensation without danger of overheating the vapors. At each pile of trays the vapors are divided. The skunk reacts with the substance, forming a metallic sulfur compound, which remains on the trays. Other products of the reaction pass off with the oil-vapors. In the chambers F in the duct the vapors of the dif-

ferent streams have an opportunity to mingle before they are divided again into small streams by the next pile of trays.

After traversing the tortuous vapor-duct ⁵ and passing through the piles of trays the vapors reach the top of box C and pass by the pipe 14 to the inlet of the vapor-duct c' in box C' at the bottom of said box. They pass up through such duct, being divided repeatedly into numerous small parallel streams flowing horizontally over the thin layers of asbestos and skunk-decomposing substance, and they escape with the volatile products of the skunk decomposition by the pipe 16 to ¹⁵ the condenser. They are thereby reduced to a liquid which may be subjected to any further operation which may be desired. The burning-oil fraction would be finished by the well-known sulfuric-acid and alkali treatment. The naphtha (if not previously removed, as it preferably would not be) would also have its skunk decomposed and would be finished in the usual way.

During the distillation lighter vapors of ²⁵ course first pass off and then the heavier vapors, and the heavier the vapors the higher becomes the temperature in the still A, chamber B, and purifier-boxes C C'. The vapors generated in still A enter the jacket B by the pipe 3 and pass with the vapors from the oil therein into the purifier C C' by the pipe 15. The distillation would ordinarily be stopped and the residuum drawn off after the removal of the burning oil, although heavier fractions ³⁵ could be freed from skunk in accordance with the invention.

After the skunk-decomposing substance has become sulfured and inactive, or as much so as is thought proper, and at the end of a ⁴⁰ run when the residuum has been drawn off from still A and chamber B, the communication of the still and condenser with the purifier and its jacket is cut off by applying a plate to the flange 2' over the end of pipe 2 ⁴⁵ and by removing the pipe-sections 3' and 16'. The outer end of that portion of pipe 3 which is attached to the jacket B, and also the upper end of pipe 15, is closed, and the outer end of the part of pipe 16 which is attached ⁵⁰ to the box C' is left open or is connected, as desired. The chamber B is next supplied with water at ordinary temperature by the pipe 18 to a little below the level of such pipe, after which no further supply of water is necessary, at least under ordinary conditions. ⁵⁵ One or more of the air-inlet pipes 20 and 21 are opened and a draft is established, as, for example, by an aspirating steam-jet, (indicated at 16².) The skunk-decomposing substance spontaneously ignites and burns with an active combustion. Preferably all the air-inlets are left open, so that the combustion is maintained on all floors at the same time. Owing to the thinness with which the ⁶⁵ skunk-decomposing substance is disposed on its supports, the combustion is readily con-

trollable by regulating, when necessary, the admission of air through the air-inlet pipes and by the cooling effect of the water in the jacket B. The use of adjustable covers or ⁷⁰ of perforated plates or reducers at the outer end of each branch will serve to regulate the air admissions, or the pipes might have the right bore to be left fully open. The disposition of the skunk-decomposing substance ⁷⁵ on its supports allows the air access without raking, and the products of combustion pass through the vapor-duct to escape by the pipe 16.

A practical test is so to adjust the air ad-

mission that the combustion goes on actively enough to boil the water in the jacket B vig-

orously without going beyond the production of a dull redness in the dark, as seen through the air-inlet at the early part of the opera-

tion. Such glow would soon disappear, and it is not necessary for it to appear even in the early part of the combustion. With a proper air admission the copper-sulfur com-

ound burns without flame and is soon con-

verted into a mixture (in greater or less pro-

portions) of copper sulfate and copper oxid.

Sulfur dioxid is given off and may be detected in the gases from the pipe 16 by its odor.

When the water in jacket B ceases to boil, the revivification may be considered complete,

the air-inlets closed, and the purifier, with its contents, allowed to cool. For a purifier hav-

ing a tortuous vapor-duct whose cross-section is three feet wide and seventeen and a half ⁹⁵ inches high, with ten piles of trays to each

floor of the duct, with thirty-six trays to a pile, and with an original quarter-inch layer

of a skunk-decomposing purifier, prepared as hereinbefore described, on each tray, one ¹⁰⁵

air-inlet pipe may be used for each floor with an inlet-opening two inches in diameter, that

diameter of opening being maintained with-

out change throughout the revivification, a

quarter-inch jet of steam, under a boiler-

pressure of sixty pounds per square inch, be-

ing maintained at 16² in the ten-inch pipe 16.

With such air-inlets the temperature will not rise too high if the substance has become fully charged with sulfur, and active combustion ¹¹⁵

will go on satisfactorily when the substance has become sulfured only to a comparatively small extent.

After the revivification the apparatus is re-

stored to the first-described state, the still A ¹²⁰ and jacket B filled with crude oil, and one or

more additional runs made, until the skunk-

decomposing substance is ready for another

revivification. If the revivified material is

a mixture of oxid and sulfate of copper, sul-

fur dioxid and water accompany the petro-

leum-vapors to the condenser, which should

preferably be lead-lined. The sulfur dioxid or

sulfurous acid may be removed and utilized.

So far as I am aware, there is no limit to

the number of times which the same charge

of substance can be revivified and reused;

but, on the contrary, my experience leads me to think that the same charge can be used indefinitely.

If the purifier is charged with the skunk-decomposing substance in an inactive condition, (say as copper sulfid,) it is made active (for example, by active combustion, as in the revivification described) before the skunk-bearing vapors are passed over it.

During the skunk decomposition and revivification the skunk-decomposing substance on the asbestos undergoes a change of state, indicated by a swollen expanded condition and attended by an increased activity of skunk decomposition. It is believed to be due to the alterations in chemical composition which the skunk-decomposing substance undergoes under conditions of temperature and pressure favorable to the retention of such an increase or expansion as may be caused by such changes. Further, it has been found that this peculiar state and the consequent fullest activity of the purifier may not be attained completely as the result of one skunk decomposition and revivification, but may require two or more such turns for their attainment.

The particular dimensions of a purifier, the particular depth of the layers of purifier, and other details are given above merely by way of illustration in order the better to enable those skilled in the art to practice the invention. They are not of the essence of the invention, and may be varied without departing from the spirit thereof.

In a number of the claims following reference is made to a non-caking temperature and an absence of compacting pressure. To avoid explanation of the expressions repeatedly in the different claims, it may here be said, once for all, that by non-caking temperature is meant one below that which would cause a union or agglomeration of the particles of the skunk-decomposing substance, and that by an absence of compacting pressure is meant a freedom from raking, grinding, or other operation sufficient to unite the particles by compression.

I claim as my invention or discovery—

1. The continuous process of removing skunk from Lima or similar petroleum, consisting in exposing a purifier composed of a refractory fibrous material like woolly asbestos and a comminuted oxid of salt of copper or like metal adherent to the fibers of such material to the vapors of such oil and (when the substance is charged with sulfur) to air so as to revivify the substance by oxidation of the metal and sulfur, all under the conditions of a non-caking temperature and an absence of compacting pressure so as to induce or retain a swelled or expanded state of extreme subdivision in the substance which adheres to the refractory fibers, and repeating the described operations under said conditions of heat and pressure, without removal of said purifier from the apparatus

in which the process is carried on by the passage of skunk-bearing vapors to decompose the skunk and of air to revivify the skunk-decomposing substance, substantially as described.

2. The improvement in the art of removing skunk from Lima or similar petroleum, consisting in exposing a purifier composed of a refractory fibrous material like woolly asbestos and a finely-divided skunk-decomposing substance adherent to said refractory fibrous material to skunk-bearing vapors and to a gaseous revivifying agent under the conditions of a non-caking temperature and an absence of compacting pressure, so as to induce or retain in said substance a swelled or expanded and extremely-subdivided condition, the said substance being exposed repeatedly in its swelled or expanded and extremely-subdivided condition and while the same is still adherent to the said fibrous material to the skunk-bearing vapors and the gaseous revivifying agent under the aforesaid conditions of a non-caking temperature and an absence of compacting pressure, substantially as described.

3. The improvement in removing skunk from Lima or similar petroleum, consisting in exposing a purifier composed of a refractory fibrous material like woolly asbestos and a finely-divided skunk-decomposing substance adherent to said refractory fibrous material to skunk-bearing vapors and to air under the conditions of a non-caking temperature and an absence of compacting pressure, so as to induce or retain in said substance a swelled or expanded and extremely-subdivided condition, the said substance being exposed repeatedly in its swelled or expanded and extremely-subdivided condition and while the same is still adherent to the fibrous material to skunk-bearing vapors and air under the aforesaid conditions of a non-caking temperature and absence of compacting pressure, substantially as described.

4. The improvement in the art of removing skunk from Lima or similar petroleum, consisting in exposing a purifier composed of a refractory fibrous material like woolly asbestos and a finely-divided skunk-decomposing substance in the form of an oxid or salt of copper or like metal adherent to said refractory fibrous material to skunk-bearing vapors and to air under the conditions of a non-caking temperature and an absence of compacting pressure, so as to induce or retain in said substance a swelled or expanded and extremely-subdivided condition, the said substance being exposed repeatedly in its swelled or expanded and extremely-subdivided condition and while the same is still adherent to the said fibrous material to the skunk-bearing vapors and air under the aforesaid conditions of a non-caking temperature and an absence of compacting pressure, substantially as described.

5. The process of preparing a purifier,

consisting in causing a skunk-decomposing substance to adhere in a finely-divided state to a refractory fibrous material like woolly asbestos, and while the said substance is so adherent subjecting it to skunk-bearing vapors and to a gaseous revivifying agent under the conditions of a non-caking temperature and an absence of compacting pressure, so as to induce or retain a swelled or expanded state of extreme subdivision in said substance, substantially as described.

6. The process of preparing a purifier, consisting in causing a skunk-decomposing substance to adhere in a finely-divided state to a refractory fibrous material like woolly asbestos, and while the said substance is so adherent subjecting it to skunk-bearing vapors and to air under the conditions of a non-caking temperature and an absence of compacting pressure, so as to induce or retain a swelled or expanded state of extreme subdivision in said substance, substantially as described.

7. The process of preparing a purifier, consisting in causing a skunk-decomposing substance having a basis of copper or like metal to adhere in a finely-divided state to a refractory fibrous material like woolly asbestos, and while the said substance is so adherent subjecting it to skunk-bearing vapors and to air under the conditions of a non-caking temperature and an absence of compacting pressure, so as to induce or retain a swelled or expanded state of extreme subdivision in said substance, substantially as described.

8. The improvement in the art of removing skunk from Lima or similar petroleum by a continuous process, consisting in passing the skunk-bearing vapors in small horizontally-flowing streams over layers of a purifier composed of a refractory fibrous material and a finely-divided skunk-decomposing substance adherent to the fibers of said material, and revivifying such substance by passing over said layers similar streams of air or gaseous revivifying agent so as to leave the said substance adherent to said fibers in a finely-divided condition for repeated action, substantially as described.

50 9. The improvement in the art of removing skunk from Lima or similar petroleum, con-

sisting in causing a skunk-decomposing substance in a solid finely-divided state to adhere to a refractory fibrous material, supporting the so-produced purifier in a way to give 55 aeriform fluid access to said substance without disturbing the purifier, passing the skunk-bearing vapors over the so-supported purifier when the substance is in the active condition, and effecting revivification by an 60 active combustion of the so-adherent spent substance, which combustion oxidized both the sulfur and the metal and leaves the revivified substance in a solid finely-divided condition adherent to the refractory fibers, 65 substantially as described.

10. The method of revivification, consisting in producing an active combustion of the sulfured substance, while this is adhering to a refractory fibrous material and is so supported as to give the air access thereto without raking or similar disturbance, and controlling such combustion by the aid of a cooling medium at a temperature indicated by dull redness or blackness, substantially as 75 described.

11. The improvement in the art of removing skunk from Lima or similar petroleum, consisting in vaporizing the oil, and subjecting the vapors to a purifier composed of a refractory fibrous material and a finely-divided skunk-decomposing substance, the temperature of which purifier is maintained by the heated oil in distillation, substantially as described. 80

12. The improvement in the art of removing skunk from Lima or similar petroleum, consisting in vaporizing the oil, and passing the vapors in numerous horizontally-flowing streams over layers of a purifier which is 90 composed of a refractory fibrous material and a finely-divided skunk-decomposing substance adherent thereto and whose temperature is maintained by means of the heated oil in distillation, substantially as described. 95

In testimony whereof I affix my signature in presence of two witnesses.
